UNITED STATES PATENT OFFICE.

WILLIAM T. FITZ GERALD, OF WASHINGTON, DISTRICT OF COLUMBIA.

POCKET CIGARETTE-MAKING DEVICE.

SPECIFICATION forming part of Letters Patent No. 587,570, dated August 3, 1897.

Application filed October 7, 1896. Serial No. 608,133. (No model.)

To all whom it may concern:

Be it known that I, WILLIAM T. FITZ GERALD, a citizen of the United States, residing at Washington, in the District of Columbia, 5 have invented certain new and useful Improvements in Pocket Cigarette-Making Devices; and I do hereby declare the following to be a full, clear, and exact description of the invention, such as will enable others skilled 10 in the art to which it appertains to make and use the same.

My invention relates to devices for forming cigarettes, and has for its object the production, in convenient and portable shape suitable for pocket use, of a comparatively simple, cheap, and efficient machine for facilitating the manufacture of cigarettes for individual consumption.

By the employment of my device a smoker 20 is enabled to make for himself as often as he desires a symmetrical and perfectly constructed cigarette from tobacco of his own selection, and thereby to insure against the presence of harmful adulterants, such as 25 opium or the like, which, as is well known, is liable to be an ingredient of the commercial cigarette.

In the accompanying drawings, Figure 1 is a perspective view of one form of my machine. 30 Fig. 2 is a longitudinal central section thereof. Fig. 3 is a transverse section of the casing, showing the mandrel removed. Fig. 4 is a side elevation of the paper-holding stopper. Fig. 5 is a perspective view of a modified form 35 of mandrel detached. Fig. 6 is a transverse section of Fig. 5 on line A A. Fig. 7 is a perspective view of a modified form of embodiment of my invention. Fig. 8 is a sectional view of the cigarette-forming tube or mandrel 40 shown in Fig. 2. Fig. 9 is a sectional view showing the tubular case and mandrel within the same, the latter being in the initial position of engaging with a sheet of paper and drawing it into the case.

Referring to the figures on the drawings, 1 indicates a tubular case, and 2 a rotatable mandrel or shaper, which in practice works 45 concentrically within the case.

The mandrel 2, with or without the case 1, 50 used with a suitable tobacco packing and ejecting device, as a rammer-stick, constitutes the essential feature of my invention in its

simplest form of embodiment. When employed, the case 1 is adapted to coöperate with the mandrel 2 in the formation of the complete cigarette. In some instances the case 1 constitutes a preferred accessory of the invention, while in others it may be entirely dispensed with, and, as above stated, the mandrel may be employed independently of it. 55

The case and mandrel when employed together are designed to coöperate to form between their opposing walls a tubular paper cigarette-wrapper 3, the mandrel constituting a rigid removable mold or shaper for a tobacco filler or core which when the mandrel is withdrawn from the paper tube 3 takes the place of the mandrel therein and completes the cigarette. 60

To adapt the mandrel to the performance 70 of the function of forming the tube 3, I provide upon one side thereof a paper-engaging device or mechanism—for instance, a longitudinally-disposed strip or lip 4. The mandrel is tubular and preferably cylindrical. The 75 lip 4 may be formed of a separate piece, brazed or otherwise secured to the exterior wall of its cylindrical body, as shown in Fig. 6, or the mandrel may be made of a single voluted sheet, as shown in Fig. 8, the part correspond- 80 ing to the lip 4 being formed by the overlap 5. The lip 4 should be approximately of a length corresponding to the length of the cigarette that the machine is designed to produce. 85

In the wall of the case 1 I provide a narrow oblong slit 6, substantially coextensive with and parallel to the strip 4. Through the slit 6 paper to be formed into a cigarette-wrapper is designed to be passed into the recess provided for it between the wall of the mandrel and its lip 4. 90

I prefer to provide the mandrel 2 with a permanent or detachable flared or funnel-shaped mouth 7 to facilitate the introduction 95 of tobacco into the interior of the mandrel.

The case 1 is provided at one end with a contracted throat, defined as by an overhanging annular flange 8, within which fits the mandrel. Upon its opposite end the case 1 100 is preferably provided with a removable stopper 9, that fits snugly within the case, and is provided upon its inner side with portions of stripping mechanism consisting of

resilient arms 10, which may be, for example, four in number. They may be made of a single piece of resilient metal pivotally secured to the stopper, as by a headed screw 5 or rivet 11.

- The arms 10 are designed to afford means, when deemed necessary, for facilitating the removal from the mandrel of a completed paper tube 3, and are for that purpose not only 10 rendered, by means of the headed screw 11, independent of the movement of the stopper 9, but are also expanded by their resiliency into contact with the inner walls of the case 1. Inasmuch, however, as it is necessary to 15 provide means for the insertion of the walls of the paper tube 3 between the arms 10, or more particularly the retaining-points 12, with which they are respectively supplied, I provide, as a means for compressing them, 20 beveled faces 13 upon their upper ends. When the mandrel is inserted into the operative position within the case 1, engaging with the lower end of the mandrel, said beveled faces cause the arms to enter the same 25 and force them out of contact with the walls of the case 1, as shown in Fig. 2, thereby affording space around said points for the introduction of the paper tube 3 between them and the wall of the case.
- 30 Designed to coöperate with the paper-holding device illustrated in detail in Fig. 4 is the herein-described mechanism for holding the tobacco against withdrawal when the mandrel is withdrawn from the paper tube 35 formed around it. Such mechanism consists, preferably, in connection with the case 1 and mandrel 2 combined, of a stripper plate or disk 14, that enters the mandrel through a transverse slot 15 near its flared end 7, and 40 which, fitting loosely within the mandrel, is sustained in place by a rod 16, that passes through an aperture in the wall of the case 1, and is thereby supported substantially at right angles to the mandrel.
- 45 To accommodate the rod 16 without interfering with the necessary amount of endwise movement of the mandrel, I provide in the latter a slit 17, (clearly shown in Fig. 5,) which is adapted to receive the rod 16 during 50 the longitudinal movement of the mandrel. I prefer that the slit 17 should not extend entirely to the lower end of the mandrel, but that its lower end should be closed, as indicated at 18. By this provision the entire removal of the mandrel from the case is prevented so long as the disk 14 is inclosed by 55 the walls of the mandrel.
- To assist the stripper-plate in its office, I prefer to provide upon it diametrically opposite to the rod 16 a lug 16^a, that works in a slit 17^a in the mandrel opposite to and corresponding with the slit 17 and enters a recess 18^a in the case 1.

It was suggested at the outset that the case 60 1 and mandrel 2, with their coöoperative parts hereinbefore specified, constitute the essential features of my invention. I prefer, how-

ever, to facilitate the manipulation of the tube and mandrel by providing an additional compartment which, serving to present to 70 the grasp of the operator a more extensive surface, at the same time affords space for the accommodation of matches, paper, and the like accessories to the cigarette-machine proper. 75

In Figs. 1, 2, and 3-a form of the device is illustrated to accommodate matches and sheets of cigarette-paper in book form. As shown clearly in Fig. 3, I prefer to make the sides of a single sheet extending from the 80 line 19 around the case 1, back in a parallel direction, and across the line of juncture 19, and thence to the line 20. The case being thus divided into a compartment 21, which, being available as a match-safe, may be denominated the "match-compartment," and a pocket 22, adapted to hold a book of cigarette-paper, its opposite ends may be closed by a top plate 23 and a bottom plate 24, the latter being provided with a door 25. In that form 85 of construction the case 1 may be completed by an inner curved wall 26, which forms a partition between the case and the compartment 21. Within one corner of the compartment may be provided a rammer-sheath 27, 90 within which fits snugly a rammer 28, that fits the mandrel 2, which is designed to afford means for packing tobacco within the mandrel. In this form of my device the rod 16 is elongated and extends through an aperture 29 in the rear of the outer case, beyond 95 which it is provided with a knob-like handle 30. To prevent the entire withdrawal of the disk from the aperture in case 1, I provide the stop-pin 30^a upon rod 16. Through the 100 manipulation of the handle and the rod 16, attached thereto, the disk may be pushed into or withdrawn from the slot 15, as required. I prefer to provide across the compartment 21 a partition 31, which separates 105 the matches 32 (illustrated in Fig. 2) from that portion of the compartment which contains the rod 16. Within the pocket 22 I prefer to provide a weak spring 33, that is 110 designed to confine the pages of a book within the pocket and prevent them from casually slipping out. Opposite the spring 33 I provide in the outer wall of the pocket a semi-circular recess 34, that permits access to the 115 paper book and affords means for extracting 120 a sheet therefrom, as required.

In Fig. 7 of the drawings I illustrate a modified form of my device adapted to accommodate a continuous roll of paper 35, the outer case 36 being provided with a semicylindrical 125 chamber 37, within which rotates in suitable bearings, as in well-known manner, a spool for the paper 35, a knurled head 38 for operating the spool being illustrated, the remaining details being omitted, as of familiar 130 construction. A slot 39 in the wall of the chamber 37 allows the paper 35 to be drawn forth for insertion underneath the lip 4. The mandrel 2 and the lip shown in this figure

may be substantially the same as those shown in Fig. 2 and are for that reason identified by corresponding numerals. A rammer 28 is shown inserted in the outer case in the opposite side of the mandrel from the chamber 37. For severing the paper 35 when required I prefer to provide in the wall of the outer case 36 a groove 40, one side of which may be defined by a sharp edge 41, formed by means 10 of an undercut 42 in the wall of the outer case 36. The operator by pressing the paper 35 against the edge 41, using his thumb-nail or a match for that purpose, may readily sever the roll when sufficient paper has been drawn 15 into the case by the mandrel to form a cigarette.

The operation of my device is as follows: The parts being in the position shown in Fig. 1 and the disk 14 being withdrawn from the 20 interior of the mandrel, the stopper 9 being in place, tobacco is supplied to the interior of the mandrel 2 and is packed therein by the aid of the rammer 28 to the desired density until the mandrel is filled almost to the level 25 of the disk 14. The mandrel is then turned until the lip 4 comes opposite to the slit 6, as shown in Fig. 1, when the paper from the book contained in the pocket 22 or from the roll 35, as may be preferred, is inserted into the 30 recess between the outer wall of the mandrel and the lip 4. Thereupon the mandrel is turned in the direction of the arrow, as shown in Fig. 9, and, as shown in that figure, the paper is caught against the edge of the lip 35 and is drawn into the slit 6. Just before it disappears within the slit the edge of the paper should be moistened, as by the tongue, so that it will adhere to the opposing wall of paper and form a cigarette-wrapper in the 40 usual manner. When the paper has entirely disappeared, the disk 14 is slipped into the slot 15 and the mandrel is ready to be withdrawn. Before withdrawing it longitudinally from the case 1 its removal may be facilitated 45 by a slight movement in the reverse direction from that indicated by the arrow in Fig. 9, which serves to disengage the edge of the lip 4 from the bend in the paper. Thereafter the mandrel may be readily withdrawn, the 50 disk 14 serving to hold the core of tobacco in place within the paper tube 3, and the latter being held by the interposition of the rod 16 and lug 16^a, as well as by pressure of the points 12 upon its walls against the interior 55 of the case 1, the arms 10, upon which the points 12 are carried, being allowed to expand by the first longitudinal movement of the mandrel. As soon as the mandrel is withdrawn the stopper 9 may be removed and the 60 completed cigarette will readily drop from the case 1.

As previously suggested, the retaining-arms 10 may be employed or dispensed with, as preferred, the stopper 9 being intended to 65 confine the tobacco within the mandrel while

it is being packed, whether the arms are employed or not.

It is obvious that the foregoing description of the operation of my device relates to that form of embodiment of my invention in which the case 1 and the mandrel 2 are combined. As previously stated, however, the case may be dispensed with and the mandrel or paper tube shaper, without its slots, may be employed independently of it in connection with 70 a suitable cigarette-ejecting device, which device may consist simply of the rammer 28. In the employment of the mandrel and rammer solely in making a cigarette the edge of a cigarette-paper may be secured by the paper-engaging device—for example, the strip or lip 4. The mandrel is then rotated between the thumb and finger of the operator until the paper is completely wrapped about 75 the mandrel.

In adjusting the paper upon the mandrel, as above described, one end of it should be allowed to project, so as to present an extension of the paper tube beyond the end of the mandrel. The projecting end of the paper tube is 80 then constricted and twisted tightly to form one end of the cigarette, previous to which operation, however, the free edge of the paper is preferably slightly moistened in the ordinary manner to cause it to adhere to the 85 contiguous part of the paper tube. After the paper has been wrapped about the mandrel and its end secured by twisting the mandrel may be filled with tobacco, the rammer 28 being employed to pack it properly. During the packing operation the twisted end of the cigarette may be supported in any suitable manner—as, for instance, by the finger of the operator. After the mandrel is properly filled and packed the end pressure upon 90 the end of the cigarette may be relieved, when a slight pressure upon the rammer will be sufficient to push out the core of tobacco from the mandrel, incidentally removing the paper wrapper formed upon the outside of the 95 mandrel. The wall of the mandrel being thin the core of tobacco will, if properly packed, slightly expand as it is ejected from the mandrel and, filling the wrapper, will drop from the end of the mandrel in the shape of a complete cigarette, symmetrical in form and 100 properly packed within its wrapper ready for the smoker.

Having thus described my invention, what I claim as new, and desire to secure by Letters 105 Patent, is—

1. In a device for making cigarettes the combination with a suitable casing, a tubular mandrel adapted to be rotated and longitudinally withdrawn from said casing and having means for engaging the edge of a cigarette-paper so that said paper may be wound around said mandrel when the same is rotated and means adapted to be inserted through the side of the mandrel designed to retain the 110

tobacco core formed in the mandrel, in place, while the mandrel is being withdrawn from the paper casing, substantially as specified and for the purpose set forth.

5 2. In a cigarette-making device the combination with a case, tubular mandrel, and means for filling the mandrel with tobacco, of a paper-wrapper-forming mechanism adapted to surround the mandrel with a paper tube, 10 and stripping mechanism adapted to strip the tobacco and paper simultaneously from the mandrel, substantially as specified and for the purpose set forth.

15 3. In a cigarette-making device the combination with a case, a longitudinally-movable rotatable tubular mandrel provided with a longitudinal slit, and means for filling the mandrel with tobacco, the case and mandrel being provided respectively with slots adapted 20 to be aligned, of a disk adapted to enter the mandrel through the slots and to be withdrawn therefrom, and a rod for actuating the disk adapted to work in the longitudinal slit in the mandrel when the mandrel is withdrawn from the case, substantially as specified and for the purpose set forth.

25 4. In a cigarette-making device, the combination with a tubular case and paper-tube shaper adapted to be longitudinally moved 30 in the case, of paper-tube-retaining mechanism in the end of the case located in the path of, and adapted to be operated by the movement of the shaper, substantially as specified and for the purpose set forth.

35 5. In a cigarette-making device, the combination with a tubular case and paper-tube shaper, of resilient arms in the end of the case adapted to retain a paper tube within the case, and beveled faces upon the arms

adapted to coöperate with the shaper substantially in the manner and for the purpose specified.

6. In a cigarette-making device, the combination with a case, a paper-tube shaper, means for introducing paper to the shaper 45 through the case and an outer case adapted to hold a continuous roll of paper for supplying the shaper and provided with a groove, of a sharply-defined edge upon one side of the groove, affording means for severing the 50 roll of paper as required, substantially as specified and for the purpose set forth.

7. In a cigarette-making device, the combination with a tubular case and paper-tube shaper adapted to form the tube in said case, 55 of paper-tube-retaining mechanism in the end of the case adapted to engage the end of a paper tube formed by the shaper, substantially as specified and for the purpose set forth.

8. As an article of manufacture, the herein-described substantially tubular mandrel adapted to be filled with tobacco and having upon its surface a paper-engaging device, substantially as specified and for the purpose set forth.

9. As an article of manufacture, the herein-described substantially tubular mandrel adapted to be filled with tobacco and having a longitudinally-disposed lip upon the surface thereof, substantially as specified and for the purpose set forth.

In testimony whereof I affix my signature in the presence of two witnesses.

WILLIAM T. FITZ GERALD.
